GARMENT SHAPING AND TURNING
MACHINE

Morris J. Rubenstein, Northampton, Pa.

Application November 26, 1935, Serial No. 51,662

3 Claims. (Cl. 223—41)

This invention relates to a shaping and turning machine for various parts of garments, such as collars, cuffs, coat lapels and the like, the general object of the invention being to provide a machine of this nature the parts of which are so constructed and arranged that a great saving of time and labor over the present method is secured as well as a uniformity of products completed on the machine.

10 This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

20 Figure 1 is an elevation of the complete device. Figure 2 is a front view of the machine.

Figure 3 is a top plan view thereof.

Figure 4 is a front view of the rear die of a 25 pair of adjustable dies used for the turning and shaping of the diagonal corners found in various parts of wearing apparel.

Figure 5 is a side view of the die shown in Figure 4.

30 Figure 6 is a front view of the rear die of a pair of adjustable dies used for turning and shaping round corners of a larger size than the die shown in Figures 1 and 2.

Figure 7 is a side view of the die shown in Figure 6.

35 Figure 8 is a front view of a die used in turning and shaping large round flaps, cuffs and the like.

Figure 9 is a side view of Figure 8.

40 Figure 10 is a front view of the rear die of a pair of adjustable dies used for turning and shaping two rounded corners at one operation, such as the collars, cuffs, etc.

Figure 11 is a side view of Figure 10.

45 Figure 12 is a front view of a die used for turning and shaping points, such as in coat lapels, flaps, vest points, etc.; and

Figure 13 is a side view of Figure 12.

In these drawings, the numeral 8 indicates a 50 base plate which is connected by screws 12 to a table or bench as shown in Figures 1, 2, and 3 and an angle bracket 9 is connected to a projecting portion of the plate 8 by the nuts 10 and this bracket is connected to the front edge of the table or bench by the screws 11. The stationary

or rear die carrying member is shown at 13 and is made in the form of a plate having its lower end bent and fastened in the base plate 8 with the rest of the plate sloping upwardly and forwardly from the bend 16. Upstanding ears 14 are formed on the base plate and form bearings for the front die carrying member 15 which is also in the form of a plate, the lower end of which is formed with a rounded enlargement having the sockets 20 in its ends. Screws 21 pass through the ears 14 and have collars thereon rotatably arranged in said ears, the threaded parts of the screws entering the sockets 20 and are held in adjusted position by the set screws 22. This arrangement permits side adjustment of the die carrying member 15 so as to permit alignment of the die carried thereby with the die carried by the rear member 13.

A spring 28 has its ends fastened to the lugs 26 on the plates 13 and 15 by the pins 27 and this spring tends to hold the front die carrying plate or member 15 away from the rear die carrying plate or member 13.

A pedal 1 is pivoted to the floor under the bench or table as shown at 2 and a chain 3 is connected by a hook 4 in an eye member 5 at the free end of the pedal. The chain is fastened to a bracket 7 connected with the die carrying member 15 and passes through a hole 19 in the die carrying member 13. The chain passes over a 25 pulley 6 rotatably supported in a carrier 17 by a shaft 18, the carrier being connected to a portion of the rear face of the member 13 and to a part of the base plate 8. Thus by pressing upon the pedal the chain will move the front die carrying member 15 toward the rear die carrying 30 member 13.

Each of the members 13 and 15 has a notch 30 formed in its upper end and plates 23 and 24 are connected by rivets 25 to the upper end of each member and extend across the entire width of each member so that these plates and the notch form a socket for receiving the reduced lower end of a die, such as that shown at 37 in Figures 1, 2, and 3. The plates 23 and 24 project upon the upper end of each member 13 and 15 and each die is formed with side extensions 29 engaging the shoulders formed by the upper end of each die carrying member 13 and 15 at the sides of the notch.

50 It will be noted that the dies bear in the sockets in such a manner that they are held in a true and rigid manner. This type of socket allows great facility in changing the dies, so highly necessary in view of the innumerable varied types 55

of work required of the machine and without the addition of any other holding devices.

As before stated the dies shown at 37 in Figures 1, 2, and 3 are for the turning and shaping of the corner of a coat pocket flap, round shirt collar and cuffs, etc.

Figures 4 and 5 show an adjustable diagonal die which is formed of the two parts 31 and 32, shaped as shown, the part 32 having a nut 33 welded thereto and the piece 31 having a socket 34 welded thereto. The part 32 rests on a portion of the upper end of the lower reduced part or stem of the part 31, and is detachable therefrom. A knurled screw 35 passes through the threads in nut 33 into the socket 34 to which it is locked by the washers 36. This type of die when placed in the socket of the die supporting member allows the operator to adjust the die for width by the turning back and forth of the screw 35 and the die is held rigid by the seating of the same in the socket. This type of die is used for the turning and shaping of the diagonal corners found in various parts of wearing apparel.

Figures 6 and 7 show an adjustable die the same as Figures 4 and 5 but the die shown in Figures 6 and 7 has its upper end rounded as shown in said views, this die being used for turning and shaping round corners of a larger size than the die shown in Figures 1 and 2.

Figures 8 and 9 show a non-adjustable die which is used in turning and shaping large round flaps, cuffs and so forth. This die is indicated by the numeral 38.

Figures 10 and 11 show an adjustable die, the adjustment of which is performed in the same manner as that shown in Figures 4 and 5. This die is used for turning and shaping two round corners at one operation such as found in collars, cuffs, etc. The two parts of this die are indicated by the numerals 39 and 40.

Figures 12 and 13 show a die 41 of the rigid type and is used for turning and shaping points such as in coat lapels, vest points and the like.

It will be understood that the dies are made and used in pairs. The number and kinds of dies to be used in this machine will be either of the rigid or adjustable type, and are shaped to perform the operation desired.

The machine is operated as follows: The operator inserts the cuffs, etc. (which have been previously sewn together) on the front die, applies pressure through the treadle, moving the front die of the front die carrying member against the die in the rear die carrying member which is stationary, which pressure locks the dies together in perfect alignment and holds the material rigidly between them. He then turns and shapes the cuffs, etc. by lifting the material up and over the dies.

It is thought from the foregoing description that the advantages and novel features of the invention will be readily apparent.

It is to be understood that changes may be made in the construction and in the combination

and arrangement of the several parts provided that such changes fall within the scope of the appended claims.

What is claimed is:—

1. In a machine of the class described comprising a support, a die-carrying member connected with the support, a second die-carrying member hingedly connected at its lower end to the support and adapted to be moved toward the first die-carrying member, each die-carrying member comprising an upstanding member having a notch formed in its upper end and a plate secured to each side of the upstanding member, said plate extending across the entire width of the upstanding member and beyond the upper end thereof to form a socket, and a pair of dies, each die comprising a stem, a part integral with a portion of the upper end of said stem, and a second part resting on a portion of the upper end of the stem and adjustable relative to the first part, each die removably and securely fitting in the socket of each upstanding member and adapted to be adjusted while in position on the die-carrying member.

2. In a machine of the class described comprising a support, a die-carrying member connected with the support, a second die-carrying member hingedly connected at its lower end to the support and adapted to be moved toward the first die-carrying member, each die-carrying member having a socket, and a pair of dies, each die comprising a stem, a part integral with a portion of the upper end of said stem, and a second part resting on a portion of the upper end of the stem and adjustable relative to the first part, each die having its stem removably fitting in the socket of each upstanding member to securely retain the die on the die-carrying member and adapted to be adjusted while in operating position.

3. In a machine of the class described comprising a support, a die-carrying member connected with the support, a second die-carrying member hingedly connected at its lower end to the support and adapted to be moved toward the first die-carrying member, each die-carrying member comprising an upstanding member having a notch formed in its upper end and a plate secured to each side of the upstanding member, said plate extending across the entire width of the upstanding member and beyond the upper end thereof to form a socket, and a pair of dies, each die comprising a stem, a part integral with a portion of the upper end of said stem, a second part resting on a portion of the upper end of the stem and adjustable relative to the first part, and extensions formed on the first and second parts, each die having its stem removably fitting in the socket of each upstanding member and having its extensions supported by the upper end of said upstanding member to securely retain the die in place on the die-carrying member.

MORRIS J. RUBENSTEIN.
